UNITED STATES PATENT OFFICE.

PAUL NICOLAS LUCAS-GIRARDVILLE, OF PARIS, FRANCE.

METHOD AND APPARATUS FOR THE STORAGE AND THE TRANSPORTATION OF GAS.

Application filed February 6, 1926, Serial No. 86,529, and in France May 20, 1925.

My invention has for its object improvements in methods and apparatus for the storage and transportation of gases. The said improvements relate chiefly to the transportation of gases which are compressed, liquefied, or dissolved at high pressure. It is a known fact that according to the usual construction, gas receptacles or containers in current use have a weight of about 10 kilo-
5 grammes per cubic meter of gas reduced to atmospheric pressure. This represents a prohibitive weight for many uses, so that efforts have been made to reduce the weight of such vessels to a considerable degree.

10 According to my invention, I substitute for the usual thick and heavy containers, a vessel with relatively thin and light walls, with the addition of means whereby the device is strengthened and protected against bursting.

15 My first means of protection consist in the application about said walls of suitable hooping which has a great tensile strength and consists of strong steel wire, known per se.

20 This method of reinforcement has already 25 been employed in artillery practice, but when the question relates to light weight containers it becomes necessary to employ special arrangements and to take suitable precautions.

25 In the artillery practice referred to, the wire hooping is wound upon the metal cylinder under a certain pressure and tension. But this method is not suitable for the construction of vessels with thin walls, since a 30 corresponding pressure of the wire would cause the distortion of the sheet metal cylinder. If a plain cylinder of thin metal were used, the winding would necessarily be so loose to avoid crushing the cylinder, that, 35 under heavy internal pressure the sheet metal would be subjected to a breaking stress before the wire would come under its normal load.

40 In the present case, therefore, the sheet metal must be allowed to expand in such manner that the stress due to the pressure shall be almost entirely supported by the wire of the hooping.

45 For this purpose I employ various arrangements certain of which are illustrated in the accompanying drawings, in which:

Fig. 1 is a diagrammatic view illustrating a cross section of one embodiment of the invention.

50 Fig. 2 is a view similar to Fig. 1 but show-

ing a different arrangement of certain parts.

Fig. 3 is a diagrammatic view illustrating a longitudinal section of a receptacle embodying the present invention.

Fig. 4 is a view illustrating in a different 60 manner the container shown in Fig. 3.

Fig. 5 is a view illustrating the crossing of two corrugations.

Fig. 6 is a view illustrating the effect as to 65 different stresses of arranging the corrugations oblique to the generatrices of the cylindrical part of the vessel or receptacle.

Fig. 7 is a view in elevation of a receiver corrugated helically.

Fig. 8 is a view illustrating other means 70 for strengthening a container.

Fig. 9 is a view of a container reinforced by the means shown in Fig. 8, part of the 75 reinforcing means being broken away to show the underlying structure; and

Fig. 10 is a view illustrating internal reinforcing means for the thin metal cylinder.

As shown in Fig. 1, the sheet metal is corrugated lengthwise of the cylinder 1 and is enclosed and compressed by tightly wound 80 wire 2 which in the cross-sectional view of this figure appears as a circle in which the section of the corrugated metal is inscribed.

When the cylinder of thin corrugated metal is expanded by internal pressure, the sheet metal may enter into substantially complete contact with the wire, which is wound loosely enough to avoid crushing the cylinder, and its enlarged circumference will become equal to the developed length of the 85 cross section of the corrugated part. Until the corrugations are drawn out, the sheet metal will not be subjected to substantial tension stress, whereas the wire is already subjected to tension. From this point onward, 90 the pressure may be increased until the sheet metal, which expands as well as the wire, attains a tension stress compatible with its strength. I suitably regulate the length and depth of the corrugations so that the sheet 95 metal as well as the wire will be subjected to the proper stresses. I may even bring the stress exclusively upon the wire, so that the sheet metal part now serves solely as a container.

100 The dimensions of the corrugations may be so calculated that although the sheet metal is not under a heavy stress when the wires have expanded to the amount corresponding to their normal stress, the sheet 110

metal will burst in the event of an increased stress upon it, and before the wires have reached the breaking point.

I thus obviate all dangerous projection of metal such as is found with the known types of cylindrical vessels which are made of strong steel. With my said device, in fact, as soon as the sheet metal yields under an excessive pressure, the gas will escape through the spaces between the hooping wires, but as the hooping remains intact there can be no projection of metal.

The relative disposition of the wire and the corrugations of the metal should be such that the vessel may resume its normal shape when the tension which expanded it ceases. When the pressure diminishes, the wire will contract and will thus compress the sheet metal, so that the metal must be guided in a certain measure in order that it may return to its initial corrugated form.

To obtain this result, I may employ suitable wires 3 placed in the lengthwise direction, one such wire being disposed in each outwardly facing trough 4 of said longitudinal corrugations. The diameter of the wire must be less than the depth of the recess or trough presented by the corrugation. When the sheet metal attains the expanded position, it will still be recessed to a certain degree, and will thus return to the initial position by its own action when the pressure ceases. Additional longitudinal wires 5 may be used in the manner indicated in Fig. 2.

I may further employ transverse corrugations 6 in the metal as shown in Fig. 3 to impart greater circumferential stiffness. In this event, the hooping may be wound under a greater tension. It will be evident that the circumferential rigidity of the cylinder depends upon the depth of the transverse corrugations.

Whatever may be the disposition adopted for the corrugations of the metal, either longitudinal or transverse, the top and bottom of the vessel will preferably consist of hemispherical members or caps 7 of pressed steel. Between these end caps there is stretched a set of wires under tensile stress, and I further employ suitable means for connecting the said vessel with the apparatus in which the gas is used. To the central part of each end is fastened, as by welding, a member, preferably of solid steel, in which is formed a tapped hole for the insertion of all such devices as expansion valves, pressure gauges, safety valves, or the like.

For connecting the end parts with the corrugated body of the vessel, precautions analogous to the preceding must be employed, so that the main sheet metal part may withstand the effects of elongation of the wires which are subjected to great stress, without any considerable tension. The cor-

rugated arrangement will also prove superior in this event, and to obtain the desired result I provide an annular expansion groove, which may be one of said corrugations 6, between the edges of the cylindrical body and the hemispherical end caps. Wires 9 may be used in said corrugations 6. The adjustment is such that the sheet metal part will serve solely as the container to prevent outward passage of gas, and the stress will come entirely upon the wires, or the sheet metal itself may take up a part of the stress within the limits of its normal strength.

There may further be employed an arrangement which comprises corrugations 10 oblique to the generatrices 11-11 of the cylindrical part of the vessel (see Figs. 6 and 7). For a very small section the corrugations may be considered as substantially straight.

Let i be the angle between the corrugations and the said generatrices; the stress due to the expansion of the sheet metal which acts directly across or perpendicular to the corrugations will have two components, one in the direction of the generatrices and the other at right angles thereto. If i is given a value near 26 degrees the other acute angle of the right triangle will be near 64 degrees, and consequently the second component will have about twice the value of the first. In these conditions, such lengthwise stress on the sheet metal is one-half the stress due to the resistance to the expansion of the cylindrical part. Internal pressure tends to exert tension on the sheet metal itself but before such action can take place directly the corrugations must be drawn out. Such expansion would act directly at right angles to the corrugations and the stress in this direction may be resolved into its components as described above.

In the aforesaid arrangement, the set of wires compensating for the traction of the end parts will be subdivided into two portions whereof one consists of wire and corresponds to the recessed part of the corrugations and the other consisting of wires 13 has the symmetrical direction and is situated at the exterior of the hooping wires 14.

Due to this subdivision of the wire into two portions, the traction of the whole set of wires upon the end parts of the recipient will be symmetrical with reference to the direction of the generatrices thus obviating the torsional effects which might occur if I employed but a single portion of wire disposed along the recessed part of the corrugations and in the oblique position as described.

In the preceding description, it has been supposed that the hooping wires are of the usual kind of circular cross section. Such wires must be in fact used for hooping pur-

poses in order to prevent the bursting of the cylinder, this being combined with a longitudinal bracing to hold the end parts in place.

- 5 But according to another form of the invention (Figs. 8 and 9) I am enabled to dispense with this double bracing, by the use of wires having a special cross section, such wires having a U section, as shown in Fig. 9, 10 and they are so disposed that the hooping of the cylinder is carried out by means of two sets of wires or hoops placed side by side, whereof each hoop 15 of one set has the opening of the U turned outwardly and 15 each hoop 16 of the other has the opening of the U turned inwardly, the two sets of hoops being connected together at their flanged edges. This arrangement offers the strength which is required both in the longitudinal and the transverse directions, so as to prevent the rupture of the cylindrical body as well as the tearing off of the end parts. In this form the cylinder 17 may 20 have outwardly projecting annular corrugations 18.

It will be further noted that the preceding arrangement is applicable to a winding which also covers the surface of the hemispherical end caps 7, so that I may use the 30 great strength of the steel wire for the construction of the said end caps, and am not restricted to the conditions depending upon the strength of the sheet metal, which is necessarily much less than that of the wire.

35 By my said method of construction, I am enabled to use sheet metal which is much thinner than the metal in common use for the manufacture of pressure recipients. But in certain cases, the vessels constructed 40 according to my said method may not have the strength necessary to withstand the usual handling. In this event I may increase their strength by the use of a light internal construction which is suitably arranged. By way of example, the said disposition may comprise: firstly a plurality of 45 light internal hoops 19 of wood or metal, assuring a regular circular form for the cylindrical surface of the vessel, secondly, a set of wires 20 serving to connect the said 50 hoops together and also to connect the hemispherical caps to the main body; thirdly, sets of wires 21 in conical disposition, serving to connect the said hoops together and 55 forming diagonal bracing members assuring the rigidity of the whole device.

The said hoops may further be connected to tension elements which assure the permanent contact between the attaching points of the wires of the longitudinal sets and the conical sets, and the sheet metal of the cylindrical part, in spite of the circumferential expansion of the cylindrical part when the vessel is subjected to pressure.

65 This result may be obtained by the use of

a device comprising the light bracing rods subjected to compression stress and forming for instance, a flat diamond shape whereof the vertices a and b are connected by wires 23 with a wire 24 attached at its ends to the hemispherical caps of the vessel. When the 70 said vessel is subjected to pressure, the said caps of the vessel will move apart, by reason of the expansion of the longitudinal wires 75 maintaining them, as above indicated. The said caps will bring together the points a and b and will hence press the vertices connected with the acute angles of the diamond strongly against the sheet metal.

The proper number of said diamond-shaped elements will depend upon the length 80 of the vessel. For containers of the usual commercial sizes, it will often be sufficient to employ two diamond-shaped elements forming two equidistant points of contact 85 with the sheet metal adjacent each of the said hoops.

By judiciously combining sheet metal of peculiarly ductile character, such as electrolytic iron, and a suitable wire, such as 90 steel piano wire, there may be made according to the present invention vessels adapted to hold material under heavy pressure and with a great reduction, 50 percent for example, of weight as compared with vessels 95 heretofore in use. These vessels may be used for the storage and transportation under heavy pressure of oxygen, hydrogen, etc. and due to the very light weight of the 100 vessels the cost of transportation will be very much reduced. An extremely important use of such vessels especially in large sizes is in the storage of fuel gases such as town gas, methane, hydrogen, etc. for use 105 in the motors of various kinds of motor vehicles. In this way certain gases, including gaseous by-products, may be utilized to great advantage especially as to efficiency 110 and economy. Another important advantage of using such gaseous by-products for motor vehicles is that the combustion of the gas may be rendered almost complete and there is substantially no such expulsion of partly burned and injurious gases as with the ordinary gasoline motor. Preferably, 115 the tanks on the motor vehicles are arranged for easy removal and replacement so that a substantially empty tank or vessel may easily be replaced by a full one. For certain purposes such as providing storage 120 for refilling of smaller containers, there may be provided tanks of large capacity which may be so large as to require the manufacture of special wire therefor.

Instead of employing mechanical means 125 to act against a possible increase in pressure, I may construct containers with relatively thin walls, by the use of physical means which prevent all excessive pressures. For this purpose I utilize the property 130

possessed by certain substances of absorbing great quantities of gas, this being the case, among others, for charcoal. These absorbents will in fact permit of disposing of a much greater volume of gas at a stated pressure in a given space than if the gas were simply compressed in a vessel of sufficient strength.

For instance 1 liter of charcoal will absorb some 4 liters of hydrogen at the ordinary temperature. I may thus store in a container of this kind some 150 cubic meters of gas per cubic meter of volume of the recipient, employing a pressure of 40 kgs. per square cm. instead of 150 kgs. according to the common practice for gas bottles. The weight of the vessels arranged in accordance with said method will be reduced from 10 kgs. to some 2.5 kgs. per cubic meter of gas contained therein the volume of the gas being measured at the atmospheric pressure.

With methane gas, I obtain a still greater advantage, since the charcoal absorbs 35 times its volume of this gas at the ordinary temperature.

It should however be noted that these effects of absorption, with the subsequent disengagement of the gas thus compressed, are accompanied by a considerable disengagement or an absorption of heat, as if the gas were liquefied within the molecules of carbon, so that if a regular absorption or disengagement of gas is desired, it is necessary to effect cooling during the filling operation and heating during the discharge operation.

It should be understood that various changes may be made in the construction and arrangement of the parts and certain features may be used without others, without departing from the true spirit and scope of the invention.

I claim:

1. A container adapted to sustain heavy internal pressure, comprising a relatively light and expansible envelope having inwardly projecting corrugations extending from end to end thereof, wire extending from end to end of the envelope and having portions lying in said corrugations, and an external reinforcement of wire so arranged around said envelope as to sustain the principal part of the stress due to the internal pressure as the envelope expands and approaches a circular cross section.

2. A container adapted to sustain heavy internal pressure, comprising an expansible cylindrical envelope of sheet metal with corrugations extending from end to end thereof, and a hooping of wire extending around said corrugations and adapted to sustain the principal part of the stress due to the internal pressure as the envelope expands.

3. A container adapted to sustain heavy internal pressure, comprising an expansible

corrugated envelope having inwardly concave ends, wire arranged transversely around said envelope, and wire arranged externally and longitudinally of said envelope to hold said ends together and to cooperate with said transversely arranged wire in sustaining the principal part of the stress due to the internal pressure as said envelope expands.

4. A container adapted to sustain heavy internal pressure, comprising an expansible longitudinally corrugated cylindrical envelope, cap portions at the ends of said envelope, wire extending from cap to cap and having portions lying in the external troughs of said corrugations, and wire arranged transversely around said envelope and cooperating with said longitudinally arranged wire to sustain the principal part of the stress as the envelope expands due to internal pressure.

5. A container adapted to sustain heavy internal pressure, comprising a relatively light and expansible envelope of corrugated sheet metal having closed ends, said envelope having a peripheral corrugation or trough adjacent each end, and external reinforcing means of wire so arranged around said envelope as to sustain the principal part of the longitudinal and peripheral stresses as the envelope expands due to internal pressure.

6. A container adapted to sustain heavy internal pressure, comprising an expansible cylindrical envelope of corrugated sheet metal having closed ends, and transverse wire hooping resisting the longitudinal pressure on said ends and outward pressure on said envelope as the latter expands, said wire hooping comprising wire of U-shaped cross section and the direction of the U-shaped sections being alternately outward and inward and successive loops of wire being locked together in this manner.

7. A container adapted to sustain heavy internal pressure, comprising an expansible longitudinally corrugated envelope of thin metal having closed ends, an outer reinforcement of wire to sustain the greater part of the stress as the envelope expands under pressure, and an inner bracing comprising light hoops and wire connecting the hoops together and connected to the ends to prevent collapse of the cylinder.

8. A container adapted to sustain heavy internal pressure, comprising an expansible cylindrical envelope of thin corrugated metal, caps attached to said envelope at its ends, an outer reinforcement of wire to sustain the greater part of the stress as the envelope expands under pressure, a longitudinal inner wire connected at its ends to the caps, and inner bracing comprising light hoops, wire connecting the hoops together, toggle means to expand one of said hoops, and connections between said toggle means and said longitudinal inner wire to operate

the toggle means when the wire is stretched.

9. A container adapted to sustain heavy internal pressure, comprising an expansible cylindrical envelope of corrugated sheet metal and having closed ends, and an external reinforcement of wire to sustain the principal part of the stress due to internal pres-

sure and comprising wires so arranged as to cause the envelope to return to its initial corrugated form when relieved from such internal pressure.

In testimony whereof I affix my signature.

PAUL NICOLAS LUCAS-GIRARDVILLE.
